UNITED STATES PATENT OFFICE

DONALD JOHN BARKER, OF COWANSVILLE, QUEBEC, CANADA

ADVERTISING STRUCTURE

Application filed September 10, 1927. Serial No. 218,646.

The invention relates to an advertising structure, as described in the present specification and illustrated in the accompanying drawings that form part of the same.

The invention consists essentially of the novel features of construction pointed out broadly and specifically in the claim for novelty following a description containing an explanation in detail of an acceptable form of the invention.

The objects of the invention are to attract the attention of the public to the various announcements setting forth the qualities of goods and the advantages that certain wares present to the consumers and to do this at the times that the persons are most susceptible to receive the information, that is to say, when they are on pleasure bent; to furnish a shelter for small and itinerant merchants requiring temporary quarters along the highways at fairs, circuses, amusement park, and other places; to eliminate the many disreputable shacks on the highways used for booths in the selling of soft drinks, refreshments, gasoline, oils and other conveniences to the traveller and replace them with neat, serviceable and bright enclosures, adding to the beauty of the roadside and to the interests of the tourists; and generally to provide a novel form of booth, which will prove of great benefit to the commercial world and of considerable service to the casual trader.

In the drawings, Figure 1 is a front elevation of the booth made of advertising signs. Figure 2 is a rear elevation of the same.

Figure 3 is an end elevation of the same.

Figure 4 is an enlarged detail of the stiffened joint of the front of the booth.

Figure 5 is an enlarged detail showing the joint broken.

Figure 6 is an enlarged detail of a corner fastening.

Figure 7 is a cross sectional view of the booth.

Figure 8 is a longitudinal sectional view of the booth.

Figure 9 is a perspective view of a roadside oil receptacle.

Like numerals of reference indicate corresponding parts in the various figures.

Referring to the drawings, in this invention in the form of a booth the roof is formed of the signs 15 and 16 or a collection of signs for each section of the roof, though to insure a good dry roof it is preferable where the dimensions will permit to have each section in a one piece sign or two pieces secured together.

The signs throughout the structure are preferably of sheet metal surfaced with a waterproof covering and the design and adapted to withstand the inclemencies of the weather and are bound with a moulding 14 though it must be understood that the construction is not confined to this particular sign as other materials may be used and answer the purpose of the invention.

The sheets of metal of the signs 15 and 16 are secured to the wooden frames 17 and 18, which are joined together by the hinges 19 and covered at the joint by the metal ridge bar 20 nailed to the frame 16 as the frame 15 is intended to fold in relation to the frame 16 and in use to move upwardly and downwardly therefrom. The end walls 21 and 22 are formed of the metal sheets 23 and 24 secured to the wooden frames 25 and 26 respectively and form at the upper ends the angular extensions 27 and 28 secured likewise to the said frames; the signs 29 being painted on these sheets and a road direction 30 such as a route number.

The back wall 31 extends from the end wall 21 to the end wall 22 and is formed of the metal sheet 32 secured to the frame 33 and surfaced and painted to complete the sign, said frame 33 being rigidly and removably secured to the frames 25 and 26 by the slotted corner brackets 34 having the slots 35 and 36 and engaging the heads of the screws 37 and 38 inserted in the frames respectively and drawing them together and forming tight corners.

The front wall 39 is low in comparison to the back wall 31 and is formed of the sheet 40 secured to the frame 41, said sheet being surfaced to complete the sign and secured to the end walls by similar corner brackets.

The counter 42 is formed of light frame work 43 suitably covered by advertising mat-

ter or plain oil cloth as found desirable and secured to the front wall 39 by similar corner brackets.

The roof section 15 is held to its open position by the struts 44 and 45, each being formed of angle bar sections 46 and 47 pivotally secured to the roof section 15 and the end walls 21 and 22 and to one another at 48, where the stiffening bars 49 stiffen the middle pivotal joints from the outer side.

The roof section 15 folds down to its closed position on the angular extensions 27 and 28 and may be locked by the hooks and eyes 50 and 51 respectively so that when the roof section is down the booth is completely closed and locked and when it is up an extension shade is formed, which protects the customers and the exposed wares from the rain or sunshine.

The walls of the booth are held down by the pegs 52 formed of tapered iron spikes secured to said walls and readily insertable into the ground. Any light platform may be used for the flooring and folding shelves may be attached to the frames on the inner sides for showing the merchandise.

The door 53 is introduced into the back wall 31 and hinged thereto and closed by the pad lock 54, this door being made of a metal sheet 55 and frame 56 and surfaced as a sign, if found desirable.

An oil box 57 is also shown as a useful road convenience to motorists and is a container for bottles of oil to keep the oil free of dust. The top 58, walls 59, 60, 61 and 62 are all made of metal sheets secured to frames and fastened by the same slotted bracket as are used in the booth, and each sheet of metal is surfaced and finished off in a design as an announcement of wares for advertising purposes.

Other structures may be made up in this fashion for advertising purposes, such as bathing houses and other enclosures used in public places, where many persons assemble or pass along.

These booths are readily assembled and therefore may be transported great distances and set up at various places, beside the highways, consequently advertisers may obtain concessions for booths and supply the ready made structures to prospective merchants.

The effects of great storms, motor accidents and other unforeseen disturbances can readily be repaired, whereas in more permanent structures the damages are not so easily cured, consequently a great convenience is furnished to the public and to the small trader at no expense to any one but the advertiser, who reaps a full harvest from the publicity.

What I claim is:—

In a collapsible booth, end walls, back walls and counter base secured together by suitable clamps, a counter rigidly secured on said base

and outwardly therefrom and a roof having a clamped rear section secured to the end and back walls and a hinged front section adapted to fold down to the counter and form with said counter base the front closure and to be elevated and form a shade.

Signed at Montreal, Canada, this 4th day of August, 1927.

DONALD JOHN BARKER.
